United States Patent Office.

MOSES A. JOHNSON, OF LOWELL, MASSACHUSETTS.

Letters Patent No. 63,798, dated April 16, 1867.

IMPROVEMENT IN MACHINES FOR FELTING OR FULLING YARN, &c.

The Schedule referred to in these Letters Patent and making part of the same.

TO ALL WHOM IT MAY CONCERN:

Be it known that I, MOSES A. JOHNSON, of Lowell, in the county of Middlesex, and State of Massachusetts, have invented certain new and useful appliances for Felting Machines, for felting wool, fur, hair, or other felting substances, either alone or mixed with cotton, flax, or other non-felting matter; and I do hereby declare the following to be a full, clear, and exact description of the same, reference being had to the accompanying drawings, making a part of this specification, in which—

Figure 1 represents a view of one side of a felting machine, arranged for felting yarns.

Figure 2 represents a vertical longitudinal section through the same; and

Figure 3 represents an elevation of the opposite side of the machine from that shown in fig. 1.

Similar letters of reference where they occur in the separate figures denote like parts of the machine in all the drawings.

My invention consists in the use of a cork surface for condensing, felting, or fulling purposes, and which is used in connection with cylinders, aprons, steam rolls, or in the presence of heat and moisture or other appliances used for such purposes.

To enable others skilled in the art to make and use my invention, I will proceed to describe the same in connection with the drawings, which represent a machine arranged for felting yarns, but which, it is obvious, is equally applicable to the condensing, felting, or fulling of any other substance that is in whole or in part capable of being so treated, and is therefore merely illustrative of the invention.

Cork possesses many peculiarities not found in any other one substance, or indeed of any manufactured substance known, and from its natural peculiarities it may be said that no substitute for cork has ever been discovered. It is pliable, elastic, enduring, not easily affected by water or steam, has a smooth and even surface, and otherwise adapted to the purposes to which I propose to apply it. The machine herein represented has in it many of the devices known and used in condensing, felting, or fulling machines, though somewhat differently combined and arranged. Its great peculiarity is, however, in the cork surface, which operates in connection with the belts, and in the presence of heat and moisture, as will be explained.

The rollers, cylinders, and belts may be driven by chains A passing over or around gears or pulleys on the several parts that are to be moved in any of the usual well-known ways. Centrally located in this machine, there is a cylinder, B, which has a perforated metallic (zinc or other metal) covering, a, over which is placed a covering, b, of cork. This cork surface may be united to the cylinder by any water-proof cement, or by sewing it, the threading passing through the perforations of the cylinder under covering, or in any other suitable manner. C C are two endless aprons, of cotton duck, or other fabric or material used for similar purposes; which aprons pass over and around the steam-heated cylinders D D, and guiding-rolls or cylinders E F G, that keep them straight, and cause them to move over or past more or less of the cork surface b, as may be required for the particular article that is being made, condensed, felted, or fulled. Within each of the belts or aprons C C there is a small pipe, e, with small perforations in it, through which small jets or a hot-water spray is thrown on to the aprons, to give them the required moisture, and as these wet aprons pass over the hot steam rolls D D sufficient heat and steam are made for felting purposes. The cork-surfaced cylinder is rotated on its journals by the friction of the travelling aprons against it, and a reciprocating motion may be given to the cylinder by the worm-gear H, shaft I, and crank-arm or pitman J, as shown in fig. 1. But, as before stated, the cork surface may be otherwise applied, or moved, for other purposes than making felted yarn, and not in immediate contact with the aprons, or with heat and moisture, and its form may be changed so long as the cork surface is used. Condensing may be done by the cork surface, as the roving comes from the card or cards, and in various modified forms of its use.

What I claim as my invention, and desire to secure by Letters Patent, is—

In combination with a cork surface, aprons, cylinders, and steam rolls, and the presence of heat and moisture for felting or fulling yarns, composed of wool, fur, hair, in whole or in part, substantially as described.

MOSES A. JOHNSON.
